UNITED STATES PATENT OFFICE.

THOMAS E. MURRAY, OF NEW YORK, N. Y.

METHOD OF AND APPARATUS FOR ELECTRIC WELDING.

1,267,256.

Specification of Letters Patent. Patented May 21, 1918.

Application filed January 21, 1918. Serial No. 212,897.

To all whom it may concern:

Be it known that I, THOMAS E. MURRAY, a citizen of the United States, residing at New York, in the county of New York and State of New York, have invented a certain new and useful Improvement in Methods of and Apparatus for Electric Welding, of which the following is a specification.

The invention is a method of and apparatus for electric welding, and more particularly for producing a projectile having means for guiding the same during flight. The said means here consist of guide vanes united to the projectile, each secured at one edge to the others and radiating from a common axis.

In the accompanying drawings:

Figure 1 is a perspective view of a guide vane section. Fig. 2 shows the assembled vanes in cross section and in place between the electrodes which weld said vanes together. Fig. 3 is a cross section of the apparatus for welding the guide vanes to the projectile, on line x, x of Fig. 5. Fig. 4 is a cross section on the line y, y of Fig. 5. Fig. 5 is a longitudinal section on the line z, z of Fig. 6, and Fig. 6 is a plan view of said welding apparatus.

Similar numbers and letters of reference indicate like parts.

The guide vanes are here shown in four similar unit sections, one of which is shown separately in Fig. 1. Each section comprises two flat plates 1, 2, preferably integral and formed by bending a single plate longitudinally at an angle of ninety degrees. At the end of each section and integral therewith is a triangular concave plate 3, shaped to fit upon the ogival end of the projectile 4. The sections are placed in contact so that the four vanes radiate from a common axis, which is concentric with the cap formed unitedly by the several juxtaposed plates 3.

I unite the vane sections by first placing two of them upon the electrodes A, A, Fig. 2, with their then vertical plates 1, 1 in contact and extending downwardly through a gap between said electrodes and an opening in the table B supporting the same. The remaining two sections are placed upon the sections already in position, with their then vertical plates 1, 1 extending upwardly through a gap between the electrodes C, C. The electrodes C, C are connected to one terminal and the electrodes A, A to the other terminal of the welding circuit. Current

being established, the electrodes C, C are pressed downwardly, whereby the meeting surfaces of the sections become welded together. Circuit being broken and the electrodes C, C raised, the united sections are rotated ninety degrees and again placed between the electrodes, with the plates 2, 2 now vertical, and the welding operation is repeated. As a result, the V-shaped plates 65 of the four sections become welded together over their meeting surfaces.

The apparatus for welding the united guide vanes to the projectile 4 is constructed as follows:

D is a fixed sleeve bolted to the table E. In said sleeve is a sliding block F having recesses suitably shaped to receive the united guide vanes and cap formed by the plates 3. Any suitable mechanism (not shown) may be connected to lever G pivoted in lugs to block F for moving said block longitudinally in said sleeve. The block F forms one of the welding electrodes. The opposite electrode H is made in two parts 5, 6. The lower part 6 is secured to and insulated from the table E, and on its upper side has a substantially semi-circular recess in which the projectile 4 is seated. On each side of the recess said part 6 is shouldered and provided with upwardly extending pairs of metal clips 7. The upper portion 5 of this electrode has a similar recess to fit upon the projectile and at each side of said recess is shouldered and provided with depending contact plates 8, which, when the projectile is in place, enter the clips 9. The opposite end of the projectile is received in a suitably formed recess in a block 10. In said end, as here shown, there is a circular opening, having a surrounding flange 11, which flange enters an annular groove in said block recess.

The block 10 is carried by a screw 12, provided with hand-wheel 13. Said screw engages in a nut 14 bolted to cross bar 15 and covering a circular opening 16 in said bar. On the fixed sleeve D and preferably integrally formed therewith are laterally projecting arms 17, Fig. 6, through which arms and the bar 15 pass tie rods 19.

The operation is as follows:

The nut 14 being released, the block 10 is removed through opening 16, together with its screw 12 and hand-wheel 13. The projectile is inserted through said opening, until the ogival end is seated in the guide vanes previously placed in position in block

6, its body portion then being received between the parts of electrode H. The upper part 5 of electrode H is pressed firmly down upon the projectile, for which purpose I 5 may provide any suitable pressing mechanism (not here shown) connected to said upper part. The block 10 is then passed through opening 16 and seated against the opposite end of the projectile, and the nut 14 is secured in place on bar 15. The adjustment of block 10 so that it will contact properly with a succession of like projectiles is effected once for all by means of the screw 12. The block F is then moved to 15 ward the projectile so as firmly to press the vanes upon the ogival end, and the welding current is established between the electrodes F, H, with the result that the vanes are welded and so immovably secured to said 20 ogival end, after which the nut 14 is again removed, and the finished projectile withdrawn through opening 16.

The center of the opening between the parts of electrode H is in line with the center 25 of the opening in electrode F, so that when the projectile is inserted in said electrodes in the manner described, its longitudinal axis is in line with said centers.

I find it preferable to provide ribs 19 on 30 the triangular plates 3, which bear upon the end of the projectile when the vanes are in place, and serve to concentrate the welding current at the welding operation.

While I have here disclosed my invention 35 as applied to the manufacture of projectiles, it is to be understood that I do not thus limit myself, since the same is applicable to the electric welding of many different objects.

40 I claim:

1. An electric welding apparatus, comprising a fixed annular electrode surrounding one of the bodies to be welded through which electrode said body passes, and an 45 electrode having a recess wherein the other body is seated and movable with reference to said fixed electrode.

2. An electric welding apparatus as in claim 1, the centers of said recess in said 50 movable electrode and of the opening in said fixed electrode being in alinement.

3. An electric welding apparatus comprising a fixed electrode surrounding one of the bodies to be welded, and an electrode 55 having a recess wherein the other body is seated and movable with reference to said fixed electrode, the said fixed electrode being formed in two sections electrically connected having recesses receiving said body, 60 one of said sections being adjustable with respect to the other section.

4. An electric welding apparatus as in

claim 1, the said fixed electrode being formed in two electrically connected sections having recesses receiving said body, 65 and, on the meeting faces of said sections respectively, contact plates and clips receiving said plates.

5. An electric welding apparatus, comprising a fixed electrode surrounding one of the bodies to be welded, and, on opposite sides of said electrode, an electrode having a recess wherein the other body is seated, and an abutment for said first-named body, the said last-named electrode being movable 75 with reference to said fixed electrode.

6. An electric welding apparatus as in claim 5, the said abutment being adjustable with reference to said fixed electrode.

7. An electric welding apparatus as in 80 claim 5, further comprising a fixed support having an opening through which said first-named body may be introduced into said electrodes, a nut covering said opening and releasably secured to said support, and a 85 screw in said nut and attached to said abutment.

8. An apparatus for electrically welding guide vanes to a projectile, comprising an electrode having recesses receiving said 90 vanes, and an electrode for supporting said projectile, one of said electrodes being movable to press said guide vanes and said projectile together at the welding joint.

9. An apparatus for electrically welding 95 guide vanes to a projectile, comprising an electrode having recesses receiving said vanes, an electrode surrounding the body portion of said projectile, and an abutment for said projectile, the said first-named electrode being movable toward said abutment 100 to press said vanes against said projectile.

10. The method of producing a projectile having a guide vane, which consists in, first, shaping said vane at one end in a configuration to correspond to that of the projectile; second, electrically welding said vane at its 105 shaped end to said projectile.

11. The method of producing a projectile having a plurality of guide vanes, which 110 consists in, first, shaping each of said vanes at one end to a configuration to correspond to that of the projectile; second, electrically welding said vanes together at a longitudinal edge of each to radiate from a common 115 axis; third, electrically welding said vanes at their shaped ends to said projectile.

In testimony whereof I have affixed my signature in presence of two witnesses.

THOMAS E. MURRAY.
